UNITED STATES PATENT OFFICE.

FREDERICK P. WESTON AND JAMES H. GRAHAM, OF TORRINGTON, CONNECTICUT,
ASSIGNORS TO THE TORRINGTON COMPANY, OF TORRINGTON, CONNECTICUT,
A CORPORATION OF CONNECTICUT.

PEDAL.

1,377,376.

Specification of Letters Patent.

Patented May 10, 1921.

Application filed January 22, 1919. Serial No. 272,468.

To all whom it may concern:

Be it known that we, FREDERICK P. WESTON and JAMES H. GRAHAM, citizens of the United States, residing at Torrington, in the county of Litchfield, State of Connecticut, have invented certain new and useful Improvements in Pedals, of which the following is a description, reference being had to the accompanying drawing and to the figures of reference marked thereon.

The invention relates to pedals for bicycles, velocipedes and motor cycles.

The object of the invention is to provide the pedal with readily removable pintles or cross bars carrying the foot-engaging rubbers or members; said pintles having a separable pivotal connection at one end with the ends of one of the pedal end pieces and adapted at their opposite free ends for engagement with open slots in the ends of the other end piece.

This object is accomplished by the construction shown in the accompanying drawing, in which—

Figure 1 is a perspective of a treadle provided with our improvements, one of the rubbers being removed and its pintle swung outwardly;

Fig. 2 is a sectional plan view thereof;

Fig. 3 is a detail showing one of the pintles in plan and side elevation;

Fig. 4 is a detail showing the two end pieces.

1 designates the pedal spindle, 2 the hub turning freely on the spindle and provided at its ends with the fixed end pieces or checks 3, 4. These parts are of the usual or any approved construction except that the end pieces are fixed on the hub, and the end piece 3 is provided with a transverse aperture 5 at each end; while the end piece 4 is provided at each end with a slot 6, open at its outer end.

7 designates the two pintles or cross bars which carry the rubber or other foot engaging members 12. These pintles 7, or cross bars, are provided at the inner end with a hook 8 and shoulder 9, and are threaded at their outer ends and there provided with a nut 10. The hooks 8 are adapted to be hooked into the transverse apertures 5 and the pintles swung inwardly until the shoulders 9 abut the inner face of the end piece 3 and the free ends of the pintles enter the

slots 6. The usual dust guard 13, having apertures 14 at its ends is now placed on the ends of the pintles 7 and the nuts 10 are placed on the threaded ends of the pintles and turned until the parts are securely held together. Washers 16 may be placed under the nuts, if desired, to frictionally hold the same from turning.

It will be seen that the pintles 7 may be readily removed upon backing off the nuts and removing the dust guard; the other parts of the pedal being untouched and in place on the spindle 1.

It is immaterial what form of foot engaging device is carried by or formed on the pintles 7, since the essential feature of the invention resides in a separable pintle and end plate construction. When a pintle is swung out as in Fig. 1, a new foot engaging rubber may be applied without removing the pintle, or the pintle may be unhooked and removed in order to remove and replace the rubber or other foot-engaging member without disassembling or disturbing the adjustment of the pedal.

In the ordinary or commonly employed pedals the pintles or cross pieces, carrying the rubbers or other foot-engaging members, are formed of long bolts which hold the end members of the pedals in place.

Having thus described our invention, what we claim as new and desire to secure by Letters Patent, is:

1. In a pedal, the combination of a hub having end pieces, pintles for the foot engaging members, means pivotally connecting the end of each pintle to one of said end pieces, means detachably connecting the opposite end of each pintle to the other end piece to permit a swinging movement of said pintles away from the hub without an endwise movement of said pintles.

2. In a pedal, the combination of a hub having end pieces, pintles for the foot engaging members, means pivotally connecting the end of each pintle to one of said end pieces, means connecting the opposite end of each pintle to the other end piece to permit a swinging movement of said pintles away from the hub without an endwise movement of said pintles, and common means to hold said pintles from such outward movement.

3. In a pedal, the combination of a hub

having end pieces, pintles for the foot engaging members, means pivotally connecting the end of each pindle to one of said end pieces, means connecting the opposite end of each pindle to the other end piece to permit a swinging movement of said pintles away from the hub without an end-wise movement of said pintles, and a dust guard closing the end of said hub and provided with means preventing free outward movement of said pintles.

4. In a pedal, the combination of a hub having end piece, pintles for the foot engaging members connected to said end piece, said connections permitting pintles to move freely away from said hub, and common means for holding said pintles from such outward movement.

5. In a pedal, the combination of a hub having fixed end pieces, pintles for the foot engaging members connected to said end pieces, said connections permitting them to move freely away from said hub, a dust guard inclosing said hub end and provided with means for holding said pintles from outward movement.

6. In a pedal, the combination of a hub having fixed end pieces, pintles for the foot engaging members, pivotally connected at one end to one of said end pieces, the other end piece having open ended slots to freely receive the opposite ends of said pintles, and a dust guard inclosing said hub and provided

with apertured extensions to receive the ends of said pintles to hold the same from movement away from said hub.

7. In a pedal, the combination of a hub having end pieces, a plurality of pintles, a foot engaging member carried by each pindle, said pintles having a pivotal connection to one of said end pieces and means for holding said pintles in engagement with the other end piece.

8. In a pedal, the combination with a hub having end pieces provided with apertured ends, pintles having hooked ends adapted to engage the apertures of one of said end pieces, the opposite ends of said pintles being adapted to engage the apertures of said other end piece, and means for securing said last named ends in position.

9. In a pedal, the combination with a hub having fixed end pieces, one of which is provided with apertured ends, and the other with open slots, in its ends, and pintles having shouldered hooks engaging said apertures, the shoulders engaging the inner face of said end, the free ends of the pintles adapted to enter said slots and provided with clamping nuts whereby the pintles may be removed without affecting the other parts of the pedal.

In testimony whereof we affix our signatures.

FREDERICK P. WESTON.
JAMES H. GRAHAM.
